O. R. ALTWEIN.

COMB.

APPLICATION FILED APR. 14, 1921.

1,388,788.

Patented Aug. 23, 1921.

UNITED STATES PATENT OFFICE.

OSCAR RICHARD ALTWEIN, OF ASHEVILLE, NORTH CAROLINA.

COMB.

1,388,788.

Specification of Letters Patent. Patented Aug. 23, 1921.

Application filed April 14, 1921. Serial No. 461,176.

To all whom it may concern:

Be it known that I, OSCAR R. ALTWEIN, a citizen of the United States, and a resident of Asheville, in the county of Buncombe and 5 State of North Carolina, have invented a new and Improved Comb, of which the following is a full, clear, and exact description.

This invention relates to improvements in combs, and more particularly to combs designed for straightening kinky hair, an object of the invention being to provide a comb in which a movable comb member operates to clamp or frictionally bind the hair between the same and teeth of a stationary member 10 or members so that when the comb is moved through the hair, it will operate to straighten the hair especially when the comb is heated.

A further object is to provide operating 20 means for the movable comb member having elastic means interposed between the operating means and the comb member, whereby a cushion compensating means is provided to prevent cutting the hair and to allow for 25 bearing thicknesses or strands of hair between the teeth of the comb. In other words, the elastic cushioning means serves to provide a cushion grip rather than a positively controlled grip which might injure 30 the hair.

A further object is to improve upon the construction illustrated in Patent No. 1,362,460, granted to me December 14, 1920.

With these and other objects in view the 35 invention consists in certain novel features of construction, and combinations and arrangements of parts as will be more fully hereinafter described and pointed out in the claims.

40 In the accompanying drawings—

Figure 1 is a view in side elevation of my improved comb.

Fig. 2 is a view in elevation at right angles to Fig. 1.

45 Fig. 3 is a view in sectional elevation with one stationary member of the comb removed to illustrate the relation of the movable member to the stationary member.

Fig. 4 is a view in transverse section on 50 the line 4—4 of Fig. 1.

Fig. 5 is a view in longitudinal section on the line 5—5 of Fig. 1.

55 My improved comb comprises a pair of stationary members 1 and 2, both having teeth 3 which come together at their free ends, and said members 1 and 2 are recessed

to accommodate a movable comb member 4, the latter having teeth 5 normally in register with the teeth 3 of members 1 and 2.

The members 1 and 2 are formed with integral recessed shanks 6 for the accommodation of the shank 7 of the movable member 4 and a pair of screws 8 are projected through one of the members 1 and screwed into the other member 2 to effectually hold the parts in proper formation, but permit an easy removal of the parts to enable them to be thoroughly cleaned so as to render the device entirely sanitary in use. These recesses along shank are to admit circulation 70 of air to reduce heat from shank and wooden handle.

A handle 9 is secured onto the shanks 6 in any approved manner and is provided with a bracket 10 on which a lever 11 is pivotally connected by means of a bolt 12. The long arm of this lever 11 is provided with a finger pad or platform 13 as a non-conductor of heat to protect the comb, and a coiled spring 14 is located in a socket 15 in the handle 9 80 and exerts outward pressure against the long end of the lever 11, said lever 11 being provided with a centering stud 16 receiving the outer end of the spring 14 to hold the latter against displacement.

This lever 11 is made with a shorter end 17 located at right angles to the longer end of the lever and movable through a slot 18 in one of the shanks 6. The free end of the shorter end 17 projects into a recess 19 in the shank 7 of movable member 4 and a coiled spring 20 is interposed between the end 17 and one end wall of the recess 19 so as to provide a cushion between said lever and the movable member to cushion the movement 95 of the movable member in one direction.

Normally the end 17 of the lever 11 is held against the end wall 22 of recess 19 by means of the spring 20, and when in this position, the teeth of the several members of the comb are in register, as shown clearly in Fig. 3. The teeth of the members 1, 2 and 4 are preferably curved longitudinally of the comb so as to give a more effectual entrance of the teeth into the hair, but it 105 is obvious that the invention is not limited to the particular shape of teeth.

It is to be understood that in operation the comb has been heated in order to produce the best results and the hair may be treated 110 with grease or liquid of any sort which will assist the operation of the comb.

In operation, the hair is placed between the teeth of the comb and the lever 11 operated by depressing the finger pad 13 toward the handle 9. The shorter end 17 of 5 the lever will engage the coiled spring 20 and exert a pressure on the movable member 4 tending to bind or grip the hair between the teeth 5 of the movable member and the teeth 3 of the stationary members 1 and 2. 10 The spring 20 will prevent any possibility of shearing the hair and hence, will compensate for an excessive number of strands between any pairs of teeth and this spring cushion, therefore, performs a most important function in the device in that it prevents injury to the hair regardless of the 15 quantity which may be between any series of teeth. The comb being heated and the strands of hair being frictionally clamped 20 with any desired pressure between the teeth and the movable and stationary members of the comb, when said comb is moved longitudinally or along the length of the hair, it will operate to iron or straighten out the 25 kink in the hair as will be readily understood.

Various slight changes might be made in the general form and arrangement of the parts described without departing from the 30 invention, and hence I do not limit myself to the precise details set forth, but consider myself at liberty to make such changes and

alterations as fairly fall within the spirit and scope of the appended claims.

I claim:

1. A comb of the character described, comprising a stationary comb member, a movable comb member, teeth on said comb members normally in alinement, means for moving the movable member, and cushioning 40 means interposed between said last-mentioned means and the movable member.

2. A comb of the character described, comprising a pair of stationary members, a movable comb member located between the stationary members, a handle fixed to the stationary members, a spring pressed lever connected to the handle, and a spring interposed 45 between the lever and the movable member.

3. A comb, comprising a pair of stationary 50 comb members, shanks on said members, a handle secured to said shanks, a movable comb member, a shank on the movable comb member movable within the shanks of the stationary members, a bracket on the handle, 55 a spring pressed lever on the bracket, the shank of said movable member having a recess therein, into one end of which said operating lever projects, and a coiled spring interposed between said lever and one end 60 of said recess, whereby the movement of the movable member by the lever is cushioned by said spring.

OSCAR RICHARD ALTWEIN.
